UNITED STATES PATENT OFFICE.

GEORGE WILLIAM COMBS, OF LEAVENWORTH, KANSAS.

BOLTING-CLOTH CLEANER.

SPECIFICATION forming part of Letters Patent No. 692,831, dated February 11, 1902.

Application filed May 3, 1900. Serial No. 15,316. (No model.)

To all whom it may concern:

Be it known that I, GEORGE WILLIAM COMBS, a citizen of the United States, and a resident of Leavenworth, Leavenworth county, Kansas, have invented a new and useful Bolting-Cloth Cleaner, of which the following is a specification.

My invention relates to cleaning devices for flour-bolters, and more especially to that 10 type of cleaner used in connection with a rotary or gyratory bolting-machine at the under side of the bolting-surface and to which motion is imparted by the motion of the machine.

15 Various means have been resorted to to keep the meshes of the silk or bolting-cloth open. Probably the most successful of these embodies a sheepskin facing in light contact with the bolting-cloth; but practical use of the 20 same discloses the following defects: First, the flour passing through the sieve upon the cleaner sifts its way down into the sheepskin facing, where it accumulates rapidly and eventually packs therein so tightly that the cleaner ceases to perform its work efficiently 25 and must be removed and cleaned by dislodging such flour; second, the sheepskin retains sharp and gritty particles, which abrade upon and soon wear out the cloth; third, although 30 the facing is under compression between the bolting and supporting surfaces, and therefore for a time properly cleans the surface of the former at all points where said bolting and supporting surfaces are substantially 35 parallel, yet it is a fact that this parallelism is disturbed at one or more points and the distance between the sifting and supporting surfaces made variable by variations in the weight of stock upon the bolting-surface, the 40 latter, of course, yielding and sinking somewhat to such pressure, and where the distance between said surfaces is least the cleaner is apt to become wedged and perform its function improperly, if at all, while if it is made 45 to accommodate such conditions its pressure upon the bolting-cloth where the latter is hardly depressed at all is so light that it performs its function inefficiently, and, fourth, the facing being soft wears away rapidly and 50 soon becomes functionless.

My object is to provide a device which cannot become clogged up with the flour or interfere with the free passage of the latter through the sieve, which will always maintain a light pressure against the bolting-cloth irrespective of the parallelism between the same and the supporting-surface and which presents less surface than the sheepskin facing for action on and thereby prolongs the period of service of the bolting-cloth. 55 6c

A further object is to produce a cleaning device of simple, cheap, and durable construction.

With these objects in view the invention consists in certain novel and peculiar features 55 of construction and combinations of parts, as hereinafter described and claimed, and in order that it may be fully understood reference is to be had to the accompanying drawings, in which— 70

Figure 1 is a vertical section of the body portion of a gyratory bolter containing cleaners embodying my invention. Fig. 2 is a top plan view of a cleaner. Fig. 3 is a vertical section taken on the line III III of Fig. 2 with 75 the cleaner proper shown in elevation. Fig. 4 is a perspective view of a modified form of cleaner.

Referring to the drawings in detail, 1 designates the casing of a bolter, 2 the stock-supply opening, and 3 a plurality of discharge-openings for the tailings and different grades of flour. 80

4, 5, 6, 7, and 8 designate sieves which increase in fineness in the order named, each 85 sieve comprising a frame 9, a silk bolting-cloth 10, stretched across the top of said frame, a coarse wire-gauze or other foraminous support 11, stretched across the bottom of the frame and substantially parallel with 90 the bolting-cloth, and one or more partitions 12, dividing the frame between the bolting-cloth 10 and foraminous support 11 into a plurality of compartments 13, in each of which is located a cleaner free to respond to 95 the various movements of the bolter and which in practice keeps the cloth meshes unobstructed and open to the passage therethrough of the stock traveling upon the cloth. 100

Referring now to the cleaner, A designates a felt or equivalent buffer of circular or other configuration and provided with a hole B. C designates a thimble, preferably of metal and flanged to provide the peripheral groove D, wherein is snugly seated the said buffer. The bottom of the thimble is of slightly-round-
5 ed or convex form and provided centrally with a hole or opening E, surrounded by an up- turned flange F, said flange being turned up-
10 ward slightly, so as to provide a rounded sur- face for contact with the wire-gauze or per-
forated support 11 and to slide thereon with a minimum of friction. The convex form of
15 the bottom, furthermore, restricts the area of frictional contact with said support.

The cleaner proper consists of an expansive spring G, almost hair-like in appear-
20 ance and of steel or any other suitable metal.
25 This spring by preference is of the spiral type, with its lower end soldered, as at H, or otherwise secured to the thimble, while its upper end is bent inward and downward slightly, as shown at I, or disposed in an equivalent manner in order to eliminate any possible chance of the end touching and abrad-
25 ing the bolting-surface.

In Fig. 4 I show a modified construction, the same comprising a buffer A, of felt or
30 equivalent material, provided with a hole B and a hair-like spring carried by the buffer for contact with the bolting-cloth, said spring consisting of the central portion J, secured to the buffer, the spring-arms K in contact
35 with the bolting-cloth, and the hinge-coils L, integrally uniting parts J and K and holding the latter upward with a light yielding pres-
sure.

Where the supporting-surface 11 of the
40 sieve is of wire-gauze or perforated metal, I prefer to reinforce the buffer with a metallic thimble, as in Fig. 3, so as to reduce the wear upon said surface.

The frame and partitions of each sieve are
45 usually of wood. For this reason a felt buffer is provided to contact with such surfaces, as metal against wood would soon indent or peck holes in the latter, as will be readily understood.

50 From the fact that my improved cleaner is of skeleton construction it is obvious that it cannot become clogged up with flour and impede the free operation, and consequently cannot catch and hold gritty particles in contact with the bolting-cloth to the injury of the latter. The thimble and buffer if non-perforated would perhaps permit of the accumulation of flour thereon; but such accumulation could not possibly attain the elevation
55 of the bolting-surface. Furthermore, by the provision of a hole in the buffer and the thimble practically all of the flour passes through the same and the foraminous supporting-surface below. It is clear, therefore,
60 that the first and second defects of a cleaner
65

embodying a sheepskin facing as enumerated above are avoided.

A cleaner consisting of a spring under light compression between the bolting and supporting surfaces will automatically accommodate itself to varying distances between said surfaces and bear with an efficient pressure against the bolting-surface at all times and under all conditions, and at the same time having a thin line of contact with the bolting-
70 surface it is always free to slide from one point to another under and in unison with the movement of the bolter, the increased pressure where the greatest depressions of the bolting-cloth occur offering practically a re-
80 sistance which the impetus given the spring by the motion of the bolter readily overcomes. The spring being of tempered steel or other metal is practically indestructible as far as the action of the bolting-cloth thereon is con-
cerned.

It is to be understood, of course, that I re-
serve the right to make such changes in the
form, proportion, detail construction, and ar-
rangement of the parts as shall not be a de-
90 parture from the spirit and scope or sacrifice
any of the advantages of the appended claims.

Having thus described the invention, what I claim as new, and desire to secure by Letters Patent, is—

1. The combination with a bolting-sieve, comprising a bolting-cloth, and a foraminous support substantially parallel therewith, of a cleaner confined between the cloth and sup-
port, consisting of a buffer resting on the sup-
port, and a spring secured to the buffer and having a thin line of contact with and exert-
ing a yielding pressure against the bolting-
cloth, and having its upper end bent down-
ward and out of contact with the bolting-
cloth, substantially as described.

2. The combination with a bolting-sieve, comprising a bolting-surface and a perforated support substantially parallel therewith, of a cleaner confined between said surface and support consisting of a metallic thimble, a buffer surrounding said thimble, and a spring projecting above the thimble and buffer, sub-
stantially as described.

3. The combination with a bolting-sieve, comprising a bolting-surface and a perforated support substantially parallel therewith, of a cleaner confined between said surface and support comprising a thimble, a buffer sur-
rounding said thimble, and a spring secured to the thimble and projecting above the same and the buffer, substantially as described.

4. A cloth-cleaner for sieves adapted to be carried by a foraminous support substantially parallel with a bolting-sieve, said cloth-cleaner consisting of a body portion and a resilient coiled-spring member secured thereto and adapted to have a portion of its coils in contact with the cloth, substantially as set forth.

5. A cloth-cleaner for sieves, adapted to be

carried by a foraminous support, arranged substantially parallel with the bolting-sieve, said cloth-cleaner consisting of a body portion provided on its under side with a shoe, and a resilient coiled-spring member projecting upwardly from the body portion and adapted to have a portion of its coils in contact with the sieve, substantially as set forth.

In testimony whereof, I affix my signature in the presence of two witnesses.

GEORGE WILLIAM COMBS.
